DESIGN FOR A COMBINED HANDBAG AND BELT

Alan B. Deitsch, New York, N. Y.

Application November 20, 1945, Serial No. 123,935

Term of patent 7 years

(Cl. D87—3)

To all whom it may concern:

Be it known that I, Alan B. Deitsch, a citizen of the United States of America, residing in New York city, county of New York, and State of New York, have invented a new, original, and ornamental Design for a Combined Handbag and Belt, of which the following is a specification, reference being had to the accompanying drawing, forming part thereof, wherein:

Figure 1 is a front elevational view of a combined handbag and belt showing my new design in assembled position.

Figure 2 is a left end elevational view.

Figure 3 is a right end elevational view.

Figure 4 is a front elevational view of the combined handbag and belt in disassembled position.

Figure 5 is a rear elevational view of the combined handbag and belt shown in Figure 1.

I claim:

The ornamental design for a combined handbag and belt, substantially as shown.

ALAN B. DEITSCH.
